UNITED STATES PATENT OFFICE

102,274

DESIGN FOR A REFRIGERATOR CASE OR THE LIKE

George J. Hopkins, Kendallville, Ind., assignor to McCray Refrigerator Company, Kendallville,
Ind., a corporation of Indiana

Application September 24, 1936, Serial No. 64,994

Term of patent 7 years

To all whom it may concern:

Be it known that I, George J. Hopkins, a citizen of the United States, residing at Kendallville, in the county of Noble and State of Indiana, have invented a new, original, and ornamental Design for a Refrigerator Case or the like, of which the following is a specification, reference being had to the accompanying drawing, forming a part thereof, in which:—

The figure is a perspective view of a refrigerator case or the like, the distinguishing, essential and dominating features or characteristics of the design being the front and sides thereof with their respective upper panels which are recessed on opposite sides of the middle panel, each of which middle panels are elevated relative to the panels on opposite sides of each middle panel, the marginal vertical elements on opposite ends of the front and its sides and the horizontal base and upper marginal elements, all of which are shown in full lines.

The opposite sides of the refrigerator case are identical in appearance and the rear side thereof is plain in character.

I claim:

The ornamental design for a refrigerator case or the like as shown and described.

GEORGE J. HOPKINS.
